UNITED STATES PATENT OFFICE.

WALTER C. MOORS, OF OWENSBORO, KENTUCKY, ASSIGNOR TO MOORS AUTOMATIC SHADE FIXTURES COMPANY, OF OWENSBORO, KENTUCKY, A CORPORATION OF DELAWARE.

SHADE-ROLLER SAFETY CATCH.

1,411,865.

Specification of Letters Patent.

Patented Apr. 4, 1922.

Application filed January 6, 1921. Serial No. 435,464.

To all whom it may concern:

Be it known that WALTER C. MOORS, a citizen of the United States, residing at Owensboro, in the county of Daviess and State of Kentucky, has invented certain new and useful Improvements in a Shade-Roller Safety Catch, of which the following is a specification, reference being had therein to the accompanying drawing.

10 The present invention relates to an improved device for automatically stopping a shade roller or other rotating member should same exceed a predetermined speed of rotation in one direction, and the invention 15 aims to provide a novel contrivance of that character, which is extremely simple and inexpensive in its construction, as well as being practical and efficient.

The present device is intended especially 20 for use with window shade rollers to prevent the roller from escaping and winding the shade up too fast, such as is apt to tear the shade, to cause annoyance in pulling the shade down, etc., as well known, although 25 the device can be used for other purposes to check or arrest the movement of a rotating member should the same rotate above an allotted speed.

The invention has for a more specific object, the provision of a novel device of that kind, including a catch to be carried by the shade roller bracket or other stationary part and a second member to be secured to and carried by the roller or other rotary member 35 for cooperation with the catch, whereby said catch is caused to stop the roller or member should same exceed a predetermined speed of rotation in one direction, such as in winding up a window shade, or the like.

40 With the foregoing and other objects in view, which will be apparent as the description proceeds, the invention resides in the construction and arrangement of parts hereinafter described and claimed, it being understood that changes can be made within the scope of what is claimed without departing from the spirit of the invention.

The invention is illustrated in the accompanying drawing, wherein:—

50 Figure 1 is an elevation of one end portion of a shade roller and its bracket, showing the device applied.

Fig. 2 is a section on the line 2—2 of Fig. 1.

Fig. 3 is a view similar to Fig. 2 showing the catch operated to lock the roller against rotation in winding up the shade.

Fig. 4 is a section on the line 4—4 of Fig. 2.

Although, for purpose of showing one embodiment of the invention, the device is shown as used for a window shade roller, it will be understood that the device can be used for other kindred purposes. In the drawing, the numeral 7 designates the shade roller upon which the window shade 8 is wound to be pulled downwardly and unwound from the roller, as usual, and such roller being usually spring-actuated to wind up the shade, as well known. A pin or spindle 9 is driven into or otherwise secured to one end of the roller and is rotatable within the bracket 10, which may represent any suitable stationary part to carry the catch as hereinafter more fully described. As shown, a metal ferrule or cap 7 is fitted over the end of the roller.

The present device consists of but two main parts or members, which can be inexpensively manufactured, and readily applied to the roller 7 and bracket 10. One member 12 is secured to the end of the roller 7, being provided with an aperture 13 through which the pin or spindle 9 can extend, and said member 12 is secured to the roller by means of a nail 14 driven through an aperture in said member into the roller, although other suitable securing means can be employed. The member 12 has the opposite rounded end portions forming tripping cams 15, and said member has shoulders 16 immediately in advance and inwardly of said tripping cams in the direction of rotation of the roller in winding up the shade.

The other part of member of the device, 95 comprises a catch 17 which is suitably pivoted, as at 18, to the bracket 10 or other stationary member, and such catch is bifurcated so as to extend astride the member 12, such catch having an upper tripper arm 19 100 to rest or bear on the member 12, and a lower stop arm 20 below or at the opposite side of said member 12. The recess between the arms 19 and 20 is rounded for the rotation of said member 12 therein, and the arm 19 is 105 provided with a cam lug 21 near the extremity thereof and at the lower side, to bear on the member 12. The lug 21 lies in

the path of rotation of the tripping cams 15, which strike and wipe past said lug, so that when the roller or member 7 rotates in one direction, such, as for example, in winding up the shade, the cams 15 in contacting with the lug 21 will have a tendency to raise the catch 17, and the greater the speed of the roller, the greater will be the upward swinging movement imparted to the catch.

10 Consequently, in operation, should the shade slip out of the hand of the person grasping the shade, or should the shade "let go" for any other reason, then ordinarily the roller would rotate at a high rate of 15 speed to wind up the shade, which would possibly damage or tear the shade, in addition to causing annoyance. However, with the present device, should the roller 7 rotate above a predetermined safe speed, the tripping cams 15 in moving at a high speed past the lug 21, will throw the catch 17 upwardly with sufficient force, to raise the stop arm 20 into the path of one of the shoulders 16, thereby stopping the roller in the manner 20 depicted in Fig. 3. Thus, referring to Fig. 2, the cam 15 which is moving into engagement with the lug 21 in moving at a sufficiently high speed, will cause the catch 17 to be swung upwardly with a sharp movement 25 so that the arm 20 will be engaged by the shoulder 16 opposite to the cam 15 which is engaging the lug 21, thereby stopping the roller. However, during normal rotation 30 of the roller to wind up the shade, the catch 35 17 is not thrown upwardly with sufficient force to catch the member 12, or the upward swinging movement of the catch may be sufficiently slow so that the shoulder 16 passes the end of the arm 20 before the catch 40 is completely raised, so that the catch will gravitate before the other shoulder 16 reaches the arm 20. By properly forming the lug 21, the action of the catch 17 will be such as to stop the roller immediately 45 when it rotates above a predetermined speed in winding up the shade, although there is no interference with the rotation of the roller below such allotted speed.

By securing the member 12 to the end of 50 the roller, and pivoting the catch 17 to bracket or member 10, the device is readily installed, and requires only a slight space or clearance between the end of the roller and bracket. As shown, the catch is 55 turned by gravity to releasing position, but it may be spring-returned, as will be obvious to the mechanic as equivalent of gravity operation.

Having thus described the invention, what 60 is claimed as new is:—

1. A device of the character described comprising a rotary member to rotate with a shade roller or the like, and a movable non-rotatable catch supported apart from said member and roller, said catch and member

having cooperable portions to stop said member and other cooperable portions to bring the aforesaid portions into cooperation when said member exceeds a predetermined speed of rotation in winding up 70 the shade.

2. A device of the character described comprising a rotary member to move with a shade roller or the like, and a pivotally-mounted non-rotatable catch supported 75 apart from said member and roller, said member and catch having portions to contact and stop said member and having other portions cooperable for swinging said catch to bring the aforesaid portions into engagement when the member rotates above a predetermined speed in winding up the shade.

3. A device of the character described comprising a member to rotate with a shade roller or the like, and a movable non-rotatable catch supported apart from said member and roller, said member and catch being cooperable to move the catch according to the speed of rotation of said member and to cooperate for stopping said member above 90 a predetermined speed of rotation in winding up the shade.

4. A device of the character described comprising a rotary member to move with a shade roller or the like, and a movable non-rotatable catch supported apart from said member and roller, said member and catch having cooperable cam portions for moving the catch according to the speed of rotation of said member and said member and catch 100 having portions to contact and stop said member when said member exceeds a predetermined speed of rotation in winding up the shade.

5. A device of the character described 105 comprising a rotary member to move with a shade roller or the like, a pivotally-mounted non-rotatable catch supported apart from said member and roller, said member and catch having cooperable cam 110 portions to swing the catch according to the speed of rotation of said member, and said catch and member having cooperable portions to engage one another and stop said member when said member exceeds a predetermined speed of rotation in winding up 115 the shade.

6. A device of the character described comprising a rotary member to move with a roller or the like, and a pivotally-mounted 120 non-rotatable catch, said catch being bifurcated and having opposite arms disposed astride said member, one arm normally bearing against said member, said arm having a cam lug, and said member having a tripping 125 cam to contact with said lug and swing the catch according to the speed of rotation of said member, and said member having a shoulder for the engagement of the other arm of said catch to stop said member when 130

said member exceeds a predetermined speed of rotation.

7. A device of the character described comprising a rotary member to rotate with a shade roller, a stationary member, and a non-rotatable catch movably carried by the stationary member and moved by the rotary

member according to the speed of rotation thereof for stopping said member should the same exceed a predetermined speed of rotation in winding up the shade. 10

In testimony whereof I hereunto affix my signature.

WALTER C. MOORS.
